UNITED STATES PATENT OFFICE.

STEPHEN KELTONIK, OF JOHNSTOWN, PENNSYLVANIA.

HEATER.

No. 927,151.

Specification of Letters Patent.

Patented July 6, 1909.

Application filed July 18, 1908. Serial No. 444,165.

To all whom it may concern:

Be it known that I, STEPHEN KELTONIK, a citizen of the United States, and a resident of Johnstown, in the county of Cambria and State of Pennsylvania, have invented a new and Improved Heater, of which the following is a full, clear, and exact description.

The invention relates to stoves and furnaces, and its object is to provide a new and improved heater, arranged to directly radiate a portion of the heat generated by the burning fuel into the room in which the heater is located, to utilize a portion of the heat for heating air to be conducted to other rooms and to provide an escape for the dust arising in the ash pit.

The invention consists of novel features and parts and combinations of the same, which will be more fully described herein-
20 after and then pointed out in the claims.

A practical embodiment of the invention is represented in the accompanying drawings forming a part of this specification, in which similar characters of reference indicate corresponding parts in all the views.

Figure 1 is a cross section of the improvement on the line 1—1 of Fig. 2; Fig. 2 is a sectional plan view of the same on the line 2—2 of Fig. 1; and Fig. 3 is a like view of the same on the line 3—3 of Fig. 1.

The body A of the heater is preferably of barrel shape, and is provided on the outside of its lower portion with vertically-extending spaced ribs A' for increasing the heat radiating surface of the body A and for reinforcing the body to prevent the same from cracking or burning when in use. The body A is provided in its bottom with an annular seat A² for a circular grate B to turn on, the 40 grate B being provided with a handle B' extending to the outside of the body A, for engagement by the operator, to enable the latter to turn the grate B.

Below the grate B is arranged an ash pit C resting on a foot D. The rear upper end of the body A is provided with a smoke flue E for carrying off the products of combustion to a chimney or the like, and the ash pit C is connected with said smoke flue 50 E by a pipe F extending outside of the body A, and serving to carry any dust that may arise in the ash pit C up into the smoke flue E and to the chimney, thus preventing such dust from passing into the room by way of the ash pit door. The front lower portion

of the body A is provided with the usual door A³ for introducing the necessary fuel.

On the flat top of the body A is arranged a dome G, having a perforate base G' fastened by bolts H to the top of the body A, and on the said base G' is secured by bolts H', a perforate conical top G² terminating in a pipe G³, employed for conducting heated air to another room or rooms. The bottom of the base G' of the dome G is formed by a hot air chamber G⁴ in the form of an inverted cone extending down into the upper portion of the body A, so that the heat and gases rising in the body A surround the hot air chamber G⁴, to highly heat the air therein, the chamber G⁴ also serving to retard the smoke and gases in the upper portion of the body A, that is, to prevent the said smoke and gases from passing too quickly to the smoke flue E. The dome G is enclosed in a mantle J, which also surrounds the upper portion of the body A and is spaced therefrom, the lower end of the mantle being open to permit air to enter the space between the body A and the mantle 80 and to cause this air to pass up and through the openings in the base G' and the top G² in the inside of the dome G, to be highly heated therein before passing through the pipe G³. Atmospheric air is also directly passed into the dome G by pipes K, extending through some of the openings in the base G' and through the space between the mantle J and the body A, the pipes also passing through the wall of the mantle J to the outside thereof, and the said pipes being preferably inclined downwardly and outwardly from the dome, as plainly indicated in Fig. 1. Now it is evident that the air passing into the dome G by way of the mantle J and the pipes K, is highly heated therein, especially as a portion of the air passes down into the hot air chamber G⁴ exposed to the high heat within the body A.

The heater shown and described is very simple and durable in construction, and is composed of comparatively few parts. By arranging the heater in the manner described, the burning fuel is utilized to the best advantage, as a portion of the heat generated by the burning fuel is directly radiated by the body A into the room, and a portion of the heat is utilized to quickly and highly heat the air passing into the dome G by way of the mantle J and the pipes K.

Having thus described my invention, I claim as new and desire to secure by Letters Patent:

- 5 1. A heater, comprising a body provided with a smoke flue, a grate in the said body, a perforate dome set on the top of the said body and having an air outlet at the top and a conical hot air chamber at the bottom, the said hot air chamber extending down into the upper portion of the said body, and a mantle inclosing the said dome and extending around the upper portion of the said body and spaced therefrom, the lower end of the mantle being open.
- 10 15 2. A heater, comprising a body provided with a smoke flue, a grate in the said body, a perforate dome set on the top of the said body and having an air outlet at the top and a conical hot air chamber at the bottom, the said hot air chamber extending down into the upper portion of the said body, a mantle inclosing the said dome and extending around the upper portion of the said body and spaced therefrom, the lower end of the mantle being open, and air pipes extending from the side of the dome outwardly and downwardly through the space between the dome and mantle and also passing through the mantle to the outside thereof.
- 20 25 30 35 40 45 3. A heater, comprising a body provided with a smoke flue at upper end, a grate in the said body, a perforate dome set on the top of the said body and having an air outlet at the top and a conical hot air chamber at the bottom, the said hot air chamber extending down into the upper portion of the said body, a mantle inclosing the said dome and extending around the upper portion of the said body and spaced therefrom, the lower end of the mantle being open, an ash pit under the said grate, and a dust pipe leading from the interior of the ash pit up through the mantle and connected with the said smoke flue.
4. A heater, comprising a body provided with a smoke flue at its upper end, a grate in the said body, a dome set on the top of the said body, said dome being formed of a conical top terminating in an air outlet and a perforate base having a conical hot air chamber extending down into the upper portion of the said body, a mantle inclosing the said dome and extending around the upper portion of the said body, and spaced therefrom, the lower end of the mantle being open, an ash pit under the said grate, and a dust pipe connecting the interior of the ash pit with the said smoke flue, the said dust pipe extending outside the said body and through the mantle.
- 50 55 60 65 70 75 80 85 90 95 5. A heater, comprising a body provided with a smoke flue, a grate in the said body, a perforate dome having a perforate base set on top of the said body, a perforate top held on the said base and provided with an air outlet and a conical bottom extending downward from the said base into the upper portion of the said body, and a mantle inclosing the said dome and surrounding the upper portion of the said body and spaced therefrom, the lower end of the said mantle being open.
6. A heater, comprising a body having a smoke flue at its upper end, a perforated dome on the top of the body and having an outlet in its top and an inlet for atmospheric air, a hot-air chamber extending into the body below the dome and in communication with said dome, a mantle inclosing the dome and through which the smoke flue passes, said mantle having a lower open end and extending down around the upper portion of the body and spaced therefrom, a grate in the lower portion of the body, an ash pit below the grate, and a dust pipe leading from the ash pit up through the mantle and connected with the smoke flue outside of the mantle.

In testimony whereof I have signed my name to this specification in the presence of two subscribing witnesses.

STEPHEN KELTONIK.
